US00D784491S

(12) **United States Design Patent** (10) **Patent No.:** **US D784,491 S**
(45) **Date of Patent:** **** Apr. 18, 2017**

(54) **TOILET RIM BLOCK**

(71) Applicant: **S. C. Johnson & Son, Inc.**, Racine, WI (US)

(72) Inventors: **Bryan C. Hale**, Gurnee, IL (US); **Steven A. Zach**, Waterford, WI (US); **Meghan Marie McGuire**, Milwaukee, WI (US); **Matthew J. Poster**, Madison, WI (US)

(73) Assignee: **S. C. Johnson & Son, Inc.**, Racine, WI (US)

(**) Term: **15 Years**

(21) Appl. No.: **29/565,026**

(22) Filed: **May 17, 2016**

(51) LOC (10) Cl. **23-01**

(52) U.S. Cl.

USPC **D23/208**

(58) **Field of Classification Search**

USPC D23/207, 208; 4/223, 227.1, 227.2, 4/227.6, 231

CPC E03D 9/02; E03D 9/03; E03D 9/05; E03D 9/032; E03D 9/038

See application file for complete search history.

Primary Examiner — Robin V Webster

(57) **CLAIM**

The ornamental design for a toilet rim block, as shown and described.

DESCRIPTION

FIG. 1 is a top, front, right perspective view of a toilet rim block showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines showing the remainder of the holder are for environmental purposes only and form no part of the claimed design.

1 Claim, 5 Drawing Sheets
